Attorney

UNITED STATES PATENT OFFICE.

LOUIS ROTHMAN, OF NORTHAMPTON, PENNSYLVANIA.

CIGAR-WRAPPER MOISTENER.

1,187,011.

Specification of Letters Patent. Patented June 13, 1916.

Application filed September 25, 1915. Serial No. 52,616.

To all whom it may concern:

Be it known that I, LOUIS ROTHMAN, a citizen of the United States, residing at Northampton, in the county of Northampton and State of Pennsylvania, have invented 5 certain new and useful Improvements in Cigar-Wrapper Moisteners, of which the following is a specification, reference being had to the accompanying drawings.

10 This invention comprehends certain new and useful improvements in cigar makers' appliances or accessories, and relates particularly to a device for moistening cigar wrappers.

15 To those familiar with the art to which this invention appertains, it is well known that it has heretofore been customary for cigar makers to moisten a heavy cloth and lay same directly on the wrappers, the cloth 20 and the moisture coming in direct contact with the wrappers, and thereby causing them to become water spotted, and with a knowledge of these conditions, my invention has for its primary object a novel and 25 useful device whereby the wrappers may be readily maintained in a properly moistened condition, and whereby all liability of their becoming spotted by the water will be precluded. And the invention also aims to 30 generally improve devices of this class so as to render them more useful and commercially desirable.

With these and other objects in view, as will more fully appear as the description 35 proceeds, the invention consists in certain constructions, arrangements and combinations of the parts that I shall hereinafter more fully describe and claim.

For a full understanding of the invention, 40 reference is to be had to the following description and accompanying drawing, in which,

Figure 1 is a perspective view of a device 45 constructed in accordance with my invention, a part being broken out for purposes of illustration. Fig. 2 is a fragmentary perspective view of one end of the trough or water receptacle of the device. Fig. 3 is a transverse sectional view on the line 3—3 50 of Fig. 1, and Fig. 4 is a section taken substantially on the line 4—4 of Fig. 1.

Corresponding and like parts are referred to in the following description and designated in all of the views of the accompanying drawing by like reference characters.

Referring to the drawing, "A" designates

as a whole the trough or water receptacle of my improved moistening device for cigar wrappers, the same being preferably constructed of sheet metal suitably shaped and 60 soldered or otherwise secured at the joints, and of any suitable width, depth, and length. It embodies a bottom 1, a relatively high rear side 2 terminating in an outwardly 65 extending flange 3, and a relatively low front side 4, which is preferably beaded at its upper edge, as indicated at 5. The trough A is provided near one end with a transversely extending partition 6 which produces, between same and the adjoining 70 end wall of the trough, a receiving compartment designed to hold one or two, or any desired number of packages of cigar wrappers, according to the size of this compartment.

75 The partition 6 has a ledge 8 secured thereto on that face thereof which forms one end wall of the water compartment, said ledge extending from the rear toward the front wall of the trough, as best illustrated in Fig. 1. A foraminous or perforated plate 10 is adapted to rest at its side edges upon these ledges 8 whereby it will slope forwardly toward the operator or workman, said plate being formed with 80 front and rear flanges 11 and any desired number of apertures 12 of any desired size and arranged in any desired way or distances from each other. In addition to the 85 openings or apertures 12, the plate is preferably formed in its middle with two relatively large openings 13 whereby the index finger and thumb of the operator's or workman's hand may be thrust through or into 90 these openings and thus hold the plate in 95 the operation of removing or applying.

The main compartment of the trough A, as distinguished from the bunch holding compartment 7, is designed to contain water, and the wrappers after being unrolled are 100 laid upon the perforated plate 11, but do not come in direct contact with the water, although they will be moistened, as is evident, and will be maintained in a properly moistened condition without becoming water 105 spotted. I also provide a cloth strip 14 of felt or the like, which has secured to one face a layer 15 of linen rubber or silk rubber, as desired, and preferably I equip each of these devices with two of these cloth strips 110 14, one with a linen rubber layer and the other with a silk rubber layer, so that the

workman may use either one, as he may see fit or as the condition of the tobacco may require. The strip 14 which is substantially co-extensive with the plate 10 and which is adapted to be laid thereon with the rubber side down, over the laid out cigar wrappers, is preferably retained in place by means of a retaining bar 16, applied thereto, and secured by screws 17 or similar fastening devices extending through the bar and through the flange 8, hereinbefore mentioned.

From the foregoing description, in connection with the accompanying drawing, the operation of my improved tobacco moistening apparatus will be apparent. In the practical use of the device, the wrappers are unrolled from the bunch and laid upon the plate 10, the water compartment containing water as is evident, and the rubber side 15 of the cloth strip 14 is suitably moistened and laid upon the pile of leaves. Thus the leaves will be maintained in a properly moistened condition while they are removed one by one and wrapped around the fillers to 25 complete the cigars.

It will thus be seen that I have provided a very durable and efficient construction of device of this kind which will be found very useful and convenient by cigar makers and 30 which will insure that the cigars will be moistened as desired and without any danger of their becoming water spotted. The plate 10 preferably slopes forward toward the operator or workman, as this will 35 render the device more convenient in use.

While the accompanying drawing illustrates what I believe to be the preferred embodiment of my invention, it is to be understood that the invention is not limited there- 40 to but that various changes may be made in the construction, arrangement and proportions of the parts without departing from the scope of the invention as defined in the appended claims.

45 What is claimed, is:

1. A moistening device for cigar wrappers, comprising a trough constituting a water receptacle, a perforated plate designed to cover said trough, and a flexible strip detachably secured to the plate adapted to be disposed over the wrappers and laid upon said plate, said strip conforming to the outer contour of the wrappers when so laid.

2. A moistening device for cigar wrappers, comprising a trough adapted to contain water, a perforated plate extending longitudinally of the trough and covering same, said plate sloping forwardly and down-

wardly from the back wall of the trough, and a cloth strip adapted to be disposed over 60 the wrappers laid upon said plate and removably secured thereto.

3. A moistening device for cigar wrappers, comprising a trough adapted to contain water, and having a relatively high rear side 65 and a lower front side, ledges extending transversely of said trough and sloping from the rear toward the front, a perforated plate adapted to rest upon said ledges and to cover the water in the trough, and a flexible strip 70 detachably secured to the plate, said strip being adapted to coöperate with the plate and the trough to provide a space in which substance may be disposed for moistening.

4. A device of the character described, 75 comprising a trough adapted to contain water, a perforated plate adapted to detachably rest upon the trough, and a cloth strip designed to be disposed over the cigar wrappers laid upon said perforated plate, and a 80 detachable retaining bar for holding said strip in place.

5. A device of the character described, comprising a trough adapted to contain water, a perforated plate adapted to cover 8 the water in the trough, said trough being formed on its rear side with an outstanding flange, a cloth strip adapted to be disposed upon the wrappers laid upon said plate, a retaining bar, and fastening devices extending through said bar and flange to hold the interposed edge of said strip.

6. A device of the character described, comprising a trough, divided into a water compartment and a smaller compartment 9 for receiving bunches of cigar wrappers, a perforated plate adapted to cover the water compartment, as and for the purpose set forth, and a flexible covering strip detachably secured to the plate.

7. In a device of the character described a liquid retaining receptacle, a foraminous cover therefor, and removable therefrom, a flexible and removable strip coöperating with the cover and adapted to partially surround and confine cigar wrappers when laid upon the cover, said cover being disposed at an angle to the surface of the liquid to permit liquid condensing on the lower face of the cover to drain into the receptacle.

In testimony whereof I hereunto affix my signature in the presence of two witnesses.

LOUIS ROTHMAN.
